UNITED STATES PATENT OFFICE

CHARLES K. PARKER, OF RICHMOND, CALIFORNIA, ASSIGNOR, BY MESNE ASSIGNMENTS, TO STANDARD OIL COMPANY OF CALIFORNIA, OF SAN FRANCISCO, CALIFORNIA, A CORPORATION OF DELAWARE

METHOD FOR THE LYE TREATMENT OF PETROLEUM OILS

Application filed August 6, 1925. Serial No. 48,489.

This invention relates to a method for the lye treatment of petroleum oils, particularly lubricating oils.

In the refinement of petroleum distillates it is generally necessary to remove acids therefrom. These acids may be either organic acids naturally occurring in the oil or organic acids formed by the action of sulphuric acid upon the oil during the refining process, or mineral acids remaining in the oil after the treatment with acid. The general practice in the art is to remove these acids by neutralizing them with a lye solution such as a solution of sodium hydroxide and then wash the oil free from the soaps and salts so formed with water. In the washing of the more viscous distillates, such as are used for lubricating oils, emulsions are formed which carry away good oil along with the impurities in the wash water. These emulsions also cause water containing impurities to remain suspended in the oil, making it difficult to wash the oil free from impurities. The emulsifying effect becomes progressively pronounced as the viscosity of the oil increases.

An object of the present invention is to provide a method and apparatus for lye treatment of petroleum oils by which such organic acids and other acids may be removed from the oils in a continuous manner and in a relatively short time and without producing any emulsion of the oil and lye solution, thus securing a purification of the petroleum oils without the normal emulsification loss of the present practice.

As a basis of the present invention it has been found that the separation of water and oil is much improved if the operation is carried out in a closed system so that the pressures above atmospheric can be maintained in the apparatus. By such a procedure the boiling point of the lye solution or water employed is raised and a much higher temperature can be used during the process.

These higher temperatures it is found cause the soaps produced by the lye treatment to become much more soluble in the water solution. Moreover, the viscosity of the petroleum oils being treated is also reduced with the result that a very rapid settling occurs. As a result of such operations the petroleum oils may be purified at a very much less loss. The color and character of the finished oil is improved by the reason of the exclusion of air from the apparatus and oil undergoing treatment, thus preventing oxidation of the oil. It is known, for example, that contact of air with a petroleum distillate tends to form appreciable quantities of gums and other residual bodies. The character of the petroleum oils produced is improved due to the reduction of the acidity of the finished oil, due to the reduction of the ash content of the oils from the more complete removal of salts, and the cost of treatment is lowered. An important feature of the invention is the carrying out of the process in a continuous manner and the invention also includes an apparatus particularly adapted for such purifying process.

Various objects and advantages of the invention will be apparent from the description of the preferred example of an apparatus and process embodied in this invention for which purpose reference is made to the accompanying drawings, which illustrate diagrammatically the preferred apparatus in which the preferred process may be conducted.

Referring to the drawings, 1 indicates a storage vessel for the petroleum oil to be treated. 1' indicates a storage vessel for the water or lye solution or other treating agent to be employed. The oil is taken from the storage vessel 1 by pump 2 and passed through lines 10 to a settling chamber 5. Cojointly therewith the treating agent is taken from storage vessel 1' by pump 2' and passed through the same line 10 to the set-

ting vessel 5. Thereby the treating agent and oil to be treated are thoroughly commingled during their passage to the settling vessel and the treating agent caused to effectively come in contact with all parts of the petroleum oil to be purified. The line 10 may lead through heat exchangers 11 and 12 during its passage to the settling chamber 5 or through a heater 3 or both as indicated. In any case the oil and treating agent is passed in the settling chamber 5 at an elevated temperature substantially above the boiling point of water. This temperature of course may be applied to the oil and treating agent prior to their admixture as well as subsequent to their admixture as is the preferred method.

The settling chamber 5 is provided with a tapered throat 4 and with a horizontal elongated central portion 8 and at the discharge end the settling chamber is enlarged as at 13 to provide for a more thorough settling of the treating agent and oil, such enlargement 13 being indicated as a vertical drum connected at its center with the elongated central drum portion 8 of the settling chamber. The portion 13 thus having an end extending below and an end extending above the intermediate part of the settling chamber 5.

The separated petroleum oil and treating agent are withdrawn from separate points from the end 13 of the settling chamber, the treating agent being withdrawn from a line 14 at the lower end and the petroleum oil from a line 15 at the upper end. The rate of withdrawal of such an oil and treating agent is regulated so that a pressure substantially above atmospheric is maintained within the settling chamber 5. The treated oil is indicated as passing through the heat exchanger 11, a line 16 being indicated by which the treated oil may be by-passed by the heat exchanger if desired and from the heat exchanger the treated oil is passed through an oil cooler 7 and pressure control valve 9 to a point of storage. The treating agent is passed through the heat exchanger 12, if desired, or it may be by-passed there-around through line 17 and is hence passed through cooler 6 and pressure control valve 10 to a point of storage.

The treating agent employed may be a caustic soda solution of sufficient quantity and strength to effect complete neutralization of the acidic bodies in the oil treated, generally considerable excess of the solution being employed to obtain a very complete neutralization of the oil. The process and apparatus is also adapted for the washing of the petroleum oil with water after such a caustic soda treatment for which purpose the oil may be passed again through the apparatus or through another similar apparatus arranged in series therewith.

While the method and apparatus herein described are well adapted for accomplishing the objects of the present invention, it is understood that various modifications may be made without departing from the spirit of the invention and the invention includes all such modifications as come within the scope of the appended claims.

I claim:

1. A process for refining petroleum oils comprising admixing the oil and an alkali solution in a conduit while continually passing the same to a settling chamber, the oil and alkali solution being heated prior to the introduction into such settling chamber to a temperature above the boiling point of water, continuously passing the admixture through the settling chamber while maintaining the same under a pressure substantially above atmospheric, and separately removing the petroleum oil and the alkali solution therefrom.

2. A process of treating petroleum oils which comprises commingling petroleum oil and a lye solution in a line while such admixture is continuously passed to a settling chamber, the admixture being heated above the boiling point of water prior to the introduction into such settling chamber continuously passing the admixture through the settling chamber while maintaining thereon a pressure greater than atmospheric, and continuously withdrawing the petroleum oil and lye solution.

3. A process of reducing the ash content of petroleum oils comprising continuously mixing oil with an alkali solution, subjecting the mixture to a temperature above 212° F. at elevated pressures until the required purification takes place, then gravitationaly separating the mixture while maintaining such elevated temperature and pressure, and continuously and separately removing treated oil and spent alkali solution.

4. A process of removing impurities from petroleum oils which comprises heating a mixture of oil with an alkaline solution to an elevated temperature and pressure, continuously passing such mixture into a settling chamber under pressure and continuously and separately removing therefrom the oil and the alkaline solution.

5. A process of treating petroleum oil which comprises continuously admixing oil with an alkali solution in a conduit, heating the mixture to a temperature above 212° F. at an elevated pressure, continuously passing the mixture into a settling chamber under pressure and continuously and separately removing therefrom the oil and alkali solutions while in the liquid phase.

6. A process of reducing the ash content of and removing impurities from petroleum oils comprising, continually mixing oil with an aqueous alkaline solution, subjecting the

5 mixture to a temperature above 212° F. at a pressure sufficient to prevent ebullition of water until the required purification takes place, then gravitationally separating the mixture while maintaining the same at an elevated temperature and pressure, and separately removing treated oil and spent alkaline solution.

10 Signed at Richmond, Calif., this 25th day of July, 1925.
